CREEL

Edward Koppelman, Huntington Park, Calif.

Application August 5, 1957, Serial No. 676,336

4 Claims. (Cl. 242—131)

This invention relates to improved creels such as are used to support yarn spools in the textile and related industries.

Previous creels such as those used in conjunction with warp beaming apparatus or directly with a loom for supplying a warp thereto are relatively heavy and bulky. Creels generally available on the market are usually of welded construction and have spool support means mounted in permanently fixed spaced relationship one to the other. The spool support means in such creels must be spaced sufficiently far apart to accommodate the largest yarn spools it is planned to use. Also, a sufficient number of such means must be provided to accommodate a relatively large number of spools such as may be used to make a warp for a tightly woven fabric of fine texture. In the latter case, the warp yarns, or ends being fine are often wound upon relatively small spools. Thus, these previous creels are relatively bulky, and in use result in an uneconomical employment of factory space. If coarse yarns are used relatively few are required in a warp of a given width, and many of the spool positions of the creel are left vacant. If, on the other hand, fine yarns are used such as are wound upon relatively small spools, the vacant space is distributed over the entire creel, but, nevertheless, the over-all size of the creel is larger than needed by a substantial factor. The problem, of course, is accentuated by the increasing demand for manufacturing flexibility and the desirability of weaving a relatively large variety of different fabrics upon the same equipment.

Another disadvantage of presently available previous creels, again stemming from their relative bulk and the permanently fixed nature of their construction is their shipping cost. Even though the creels are not exceptionally heavy, they occupy a considerable amount of space, and generally must be packaged carefully to avoid damaging them during shipment. Protruding parts such as spool support rods, and thread guide rods and plates must be protected against impacts that might bend or distort them. In some cases, the shipping costs alone, disregarding packing costs, may exceed the purchase price of these creels by a substantial margin, resulting in a gross cost to the purchaser of more than twice the price received by the seller.

Accordingly, one important object of the present invention is to provide an improved creel of relatively light weight and compact construction.

Another object is to provide an improved creel in which the spool supporting means are adjustable in position to permit maximum utilization of the space occupied by the creel.

Another object is to provide an improved creel that may be readily and quickly disassembled and compactly organized for shipping at minimum expense, and that may be easily and quickly reassembled by relatively unskilled personnel.

These and other objects are accomplished by the present invention, one embodiment of which comprises a creel

2

having vertically spaced, elongated, horizontal supporting members, or beams. Pairs of rods, each pair comprising a spool holding rod and a threaded guide rod, are horizontally supported transversely to the beams upon 5 pairs of plates. Each pair of plates is held in pressure engagement against opposite sides of a beam by a single releasable fastener extending through the plates closely adjacent to the beam. The rods extend through spaced apertures near opposite ends of the plates, one of the 10 rods being positioned below the beam, and the other one above the beam. The rods are shaped to cooperate with the beam and with the plates to maintain the assembly fixedly but removably in position upon the beam. The rods may be quickly and simply removed from the beams, together with the plates merely by removing the single fastener.

The invention will now be described in greater detail in connection with the accompanying drawing of which:

Figure 1 is a side elevational view of a portion of a creel embodying the present invention;

Fig. 2 is a fragmentary, side elevational view of a portion of the creel shown in Fig. 1, illustrating the parts thereof on a larger scale;

Fig. 3 is a cross-sectional view of a portion of the creel shown in Fig. 2, taken along the section line 3—3 thereof;

Fig. 4 is a longitudinal section of a portion of the creel shown in Fig. 3, taken along the line 4—4 thereof; and

Fig. 5 is a fragmentary cross-sectional view of the creel as shown in Fig. 4, taken along the section line 5—5 thereof.

Referring now to the drawing, the creel shown therein comprises a pair of vertical supports 10 and 12 upon which a plurality of vertically spaced horizontal beams 14 are fixed. The beams 14 may be channel-shaped as shown, 35 and may be secured by any convenient means (not shown) to the uprights 10 and 12, the manner of their attachment thereto being in no way critical in the practice of the invention, except that for convenience in shipping releasable attaching means are preferably used. A plurality of separate rod and plate assemblies are removably secured to the beams 14 for supporting spools of thread or yarn 16 and for tensioning and guiding thread 24 from the spools 16 to its point of use. Each one of the assemblies 20 includes a spool supporting rod 18, and a thread guide rod 22 over which the yarns 24 are trained when the creel is threaded. If desired, conventional perforated yarn guide plates 26 may be fixed upon the vertical support 12 at the discharge end of the creel to guide the yarn as it is drawn from the creel.

The structure of the individual supporting assemblies 20 is shown in detail in Figs. 2 to 5. The assemblies 20 illustrated herein are adapted to cooperate with beams 14 of generally rectangular or square cross section, but it will be seen that with only minor modification they may be readily adapted for use with beams of other cross-sectional shapes such as, for example, hexagonal. Each one of the assemblies 20 includes a spool supporting rod 18 and a yarn guide rod 22, supported upon a pair of plates 28 and 30, which are identical to each other in all respects except for change of hand. The plates 28 and 30 are elongated in shape and include inwardly bent ears, or tabs 32 near their lower ends, which project beneath and engage the lower surface of the beam 14. The plates 28 and 30 include upper, lower, and intermediate apertures 34, 36 and 38, respectively, spaced along their length.

The lower aperture 36, the central aperture 38 and the tab 32 define a triangle having a height roughly equal to the thickness of the beam 14, so that when the plates are assembled one on each side of the beam 14, rods or screws passed through the intermediate aperture 38

and the lower aperture 36 cooperate with the tab 32 to hold the plate against rotation on the beam 14.

The upper rod 22 is fitted through the upper apertures 34 of the pair of plates 28 and 30 and is provided with means to hold the plates in spaced apart relationship. Such means may comprise, for example, upset portions 40 as illustratively shown, struck from the rod 22 near its center, and spaced apart a distance equal to the width of the beam 14. Thus, when the plates 28 and 30 are fitted over the ends of the rod 22 and urged together, they hold the rod 22 rigidly in position and are spaced apart by the upsets 40.

The plates 28 and 30 are secured to the beam 14 by a single screw 42 which may be engaged by a nut 44. The screw 42 is passed through the intermediate apertures 38 above the beam 14 and is tightened sufficiently to hold the plates 28 and 30 firmly upon the beam 14, and to bring them into frictional engagement therewith to lock them against longitudinal displacement. The lower, or spool supporting rod 18 is bent upwardly at both ends to retain the spool 16, and to prevent the spool from "walking off" the rod as it is unwound. This spool supporting rod 18 extends through the lower apertures 36 of the plates 28 and 30 and is held against rotation by flats 46 which are formed in the rod and which bear against the lower surface of the beam 14 when the assembly is in position.

The offset position of the tab 32 with respect to the line defined by the lower and intermediate apertures 36 and 38, respectively, brings the upper aperture 34 into a position longitudinally spaced from the lower aperture 36, so that a thread drawn from a spool mounted on the support rod 18 may be looped over the upper thread guide rod 22 for tensioning purposes.

Each one of the assemblies 20 is readily adjustable in position upon the beam 14 on which it is mounted merely by loosening the screw 42 to free the plates 28 and 30 from frictional engagement with the beam. When this is done, the assembly 20 may be moved freely along the length of the beam 14, to be locked again in a new position. Moreover, the entire creel may be readily and quickly disassembled for shipment, and its component parts may be compactly packaged for shipment to provide substantial savings in shipping costs. The creel may also be made relatively light in weight since none of its parts need be welded in place. Whereas, in previous creels of welded construction, the difficulties of welding light metals such as aluminum and magnesium dictate the use of steel or iron, the structure according to the present invention is preferably made of light metals such as aluminum or magnesium in order to reduce costs, especially with respect to shipment, and also to take advantage of other well known beneficial characteristics of these light metals.

The creel may be threaded in a conventional manner, as shown, for example, in Figs. 1 and 2, wherein spools 16 are loosely supported on the lower rods 18 for unwinding in a counterclockwise direction. The threads 24 are drawn from the spools 16 rearwardly and upwardly and are looped over the thread guide rods 22, and then led forwardly and trained over the next adjacent thread guide rod 22. Tensioning weights such as the U-shaped weights 48 may be hung on the individual threads 24 in a conventional manner as shown.

It will be seen that a creel according to the invention is highly flexible in that the assemblies 20 are not only adjustable in position on the beams 14, but also may be adjusted in number to accommodate different numbers of thread spools as may be required. The creel is also adjustable vertically, and depending upon the height available in the building where it is used, its capacity may be increased by adding additional beams 14 above the ones normally used. In this connection, it may also be desired to provide means to make the vertical

spacing of the beams 14 upon the supports 10 and 12 adjustable, and if maximum efficiency of space utilization is desired, this may be done.

There has thus been described an improved creel structure that is relatively simple and inexpensive to manufacture and may be readily and quickly assembled and disassembled, and adjusted to accommodate different numbers of yarn spools of different sizes.

What is claimed is:

1. A creel comprising an elongated horizontal supporting member, a pair of symmetrically aligned plates positioned upon opposite sides of said member in frictional engagement therewith and extending above and below said member, each one of said plates including an inwardly projecting portion positioned beneath said member, a thread guide rod fitted through aligned apertures in said plates adjacent to the upper ends thereof, said thread guide rod including spacing means to support said plates in spaced apart relationship when they are pressed together, fastening means to press said plates together and to hold them in pressure engagement with said member, said fastening means being positioned above said horizontal member, a spool supporting rod fitted through aligned apertures in said plates adjacent to the lower ends thereof and horizontally spaced from said inwardly projecting portions, said spool supporting rods being outwardly upwardly bent, means to fix said spool supporting rods against rotation, and means including said inwardly projecting portions and said spool supporting rods to fix said plates against rotation about an axis transverse to said horizontal member.

2. A supporting assembly for use in a creel to support a thread spool and to guide a thread drawn therefrom, said assembly being adapted to be mounted upon a horizontally disposed elongated member and comprising a pair of supporting plates having inwardly projecting tabs, said tabs being positioned to project under and to abuttingly engage the lower surface of the supporting member when said plates are vertically positioned upon opposite sides of the member, each one of said plates having an upper, a lower, and an intermediate aperture, a spool supporting rod extending through said lower apertures of both of said plates and having a central flat portion adapted to engage the lower surface of the supporting member to hold said rod against rotation, a guide rod extending through said upper aperture of both of said plates, means centrally fixed on said guide rod to abut said plates to hold them in spaced apart relationship, and fastening means extending through said intermediate apertures of both of said plates to urge said plates towards each other and into abutting frictional engagement with the sides of the supporting member when they are disposed thereagainst, said tabs, said fastening means, and said spool supporting rod all cooperatively engaging the supporting member to restrain said assembly against rotational movement when said assembly is mounted upon the member.

3. A creel comprising an elongated horizontal supporting member, a pair of vertical plates symmetrically arranged upon opposite sides of said member, fastening means to urge said plates towards each other into pressure engagement with said member, a first rod and a second rod, extending transversely with respect to said member through aligned apertures in said plates, said first rod being spaced from said member and including central upset portions adapted to hold said plates in predetermined spaced relationship against the urging of said fastening means, said second rod being positioned in abutting relationship to said member and including a central flat portion to engage said member to hold said second rod against rotation, each one of said plates including a tab projecting transversely across said member in abutting engagement therewith, said tabs, said fastening means, and said second rod all abutting said member

and being arranged triangularly to hold said plates against rotation.

4. A creel comprising an elongated horizontal supporting member, a pair of symmetrically aligned plates positioned upon opposite sides of said member in frictional engagement with and extending above and below said member, each one of said plates including an inwardly projecting tab extending partly across and in abutting engagement with said member, fastening means to urge said plates together and into tight pressure engagement with said member, said fastening means being positioned on the vertically opposite side of said member from said tabs, a supporting rod fitted through aligned apertures in said plates and vertically positioned on the

same side of said member as said tabs, said supporting rod extending transversely with respect to and projecting outwardly from said member and including a flat portion engaging said member to restrain said rod against rotational movement, and spacer means disposed between said plates on the same side of said member as said fastening means for maintaining said plates in generally parallel relationship to each other against the urging of said fastening means.
